United States Patent Office

Des. 206,913
Patented Feb. 7, 1967

206,913

BOTTLE

David G. Hills, Canton, Conn., assignor to National Dairy Products Corporation, New York, N.Y., a corporation of Delaware

Filed Jan. 7, 1966, Ser. No. 522

Term of patent 14 years

(Cl. D58—6)

The dominant features of my design reside in the portions shown in solid lines.

I claim:

The ornamental design for a bottle, substantially as shown and described.
